United States Patent Office

Des. 202,208
Patented Sept. 7, 1965

202,208

COMBINED CAN PUNCH AND JAR OPENER

Paul F. Bolduc, R.R. 1, Starke County, Ind.

Filed Feb. 26, 1965, Ser. No. 83,986

Term of patent 14 years

(Cl. D44—29)

Fig. 1

Fig. 2

Fig. 3

FIGURE 1 is a plan elevation of the combined can punch and jar opener embodying my design;

FIGURE 2 is a plan elevational view thereof; and

FIGURE 3 is a longitudinal sectional view taken along line 3—3 of FIGURE 1.

I claim:

The ornamental design for a combined can punch and jar opener, as shown.

References Cited by the Examiner

UNITED STATES PATENTS

D. 39,508 9/08 Fritzsche ----- D44—4
2,829,432 4/58 Haslett.

EDWIN H. HUNTER, Primary Examiner.

JOEL STEARMAN, Examiner.